Laboratories, Inc., a corporation of Delaware

Application January 1, 1943, Serial No. 470,952

17 Claims. (Cl. 179—175.2)

The present invention relates in general to improvements in telephone systems and more particularly to improved arrangements for testing subscribers' lines.

In order to facilitate the testing of the various subscribers' lines which enter an exchange it is usual to provide in the exchange a centralized test desk and automatic switching apparatus by means of which it is possible to extend a test circuit from the test desk directly to the line conductors of any desired one of the subscribers' lines. Facilities of this character ordinarily include some arrangement for clearing a subscriber's line of attachments, i. e., for disconnecting from the line under test that part of the exchange equipment which is normally connected to the line conductors of such line and which, if permitted to remain connected thereto, would adversely effect the test.

While the arrangements which heretofore have been provided for clearing a subscriber's line of attachments are quite satisfactory under most conditions encountered in practice, they usually are totally ineffective in the presence of certain abnormal conditions. If, for example, a connection is extended from the test desk to a subscriber's line at a time when a "permanent" condition exists upon that line due to its conductors accidentally having become bridged and/or grounded, the conventional arrangements will not disconnect the exchange equipment attached to the line conductors, and accordingly it is not possible to perform a satisfactory test upon the line over the connection extended thereto from the test desk.

It is the general object of the present invention, therefore, to provide an improved arrangement for clearing a subscriber's line of attachments, not only under normal conditions, but under the abnormal conditions noted.

Inasmuch as the accidental bridging and/or grounding of a subscriber's line simulates a calling condition, it usually results in the partial extension of a connection from the line over switching equipment which is common to a group of subscriber's lines; it is another object of the invention to provide an improved arrangement for breaking down a connection thus extended.

As is well known, provision is sometimes made for locking out a subscriber's line on which a permanent condition exists; it is a further object of the invention to provide an arrangement for clearing a permanent line of attachments after such line has become locked out.

According to one feature of the invention, the 55

same arrangement is effective to clear a permanent line of attachments whether or not that line is arranged to lock itself out in the event of a permanent.

According to another feature of the invention, a relay, which is connected to the subscriber's line and energized thereover due to a permanent condition of the character described, is caused to restore as a result of the differential action produced in its windings by means of a booster battery potential applied to the subscriber's line over the test connection extended thereto.

Further objects and features of the invention will be apparent from the following description, reference being made to the accompanying drawing which discloses the circuits of an automatic telephone system embodying the invention.

Referring more in detail to the drawing, the telephone system shown therein includes a plurality of subscribers' substations, two of which are indicated at 100 and 300, and subscriber-controlled automatic switching equipment for setting up connections to wanted substations such as 199 and 399. This switching equipment includes links such as 140 and 340, each of which comprises a finder switch having access to calling lines and a selector switch having access to called lines over a train of one or more subsequent switches, depending upon the number of subscribers in the system. For purposes of making routine tests upon the subscribers' lines, a test desk 200 is provided, which has access to said lines over operator-controlled automatic switching equipment including a test distributor 230 and a test connector such as 280. The bank of the test connector is connected in multiple to the banks of the standard, subscriber-controlled connectors by means of which calls are extended to the various lines.

It will be observed that the showing of test desk, the test distributor, the test connector and the finder-selector links is largely schematic, only such details having been included as are necessary for the complete understanding of the present invention. Reference may be had to United States Patent No. 2,214,908, issued on September 17, 1940, to C. E. Lomax et al., for additional details of one suitable form of finder-selector link. Likewise, reference may be had to United States Patent No. 1,691,269, issued on November 13, 1928, to T. F. Crocker, for additional details of one suitable form of test distributor and test connector.

The general procedure involved in making tests upon various subscribers' lines is fully set forth

in the last-mentioned patent. This procedure will be outlined briefly, it being assumed for this purpose that the test operator wishes to test the line 101 leading to substation 100. To do this, he first closes contacts 221, 222 and 223 (which may be accomplished by inserting a plug in a jack, by operating a manual switch key, or by any like measure) thereby to seize the test distributor 230. Next, by means of a dial at the test desk 200, he operates the test distributor to seize a test connector such as 280, and then operates the test connector to move its wipers 291, 292 and 293 into engagement with bank contacts 294, 295 and 296, respectively, of the line 101.

As explained in detail in the Crocker patent, relay 250 in the test distributor is operated during the final setting of the test connector wipers upon the line to be tested, and it releases upon completion of that setting operation. Accordingly, while operated, relay 250 maintains the slow-to-release relay 260 operated over contact 252, thereby to hold the test circuit open at contacts 261 and 262 during the setting of the test connector wipers. When relay 250 restores at the end of the setting operation, it closes contact 251 and, at contact 252, opens the circuit for relay 260. Because of its slow-to-release characteristic, relay 260 remains operated for a brief interval after its circuit is opened, and then restores; during this interval, in order to determine whether the line 101 is busy or idle, the test relay 240 is connected to contact 296 in the bank of the test connector, over the following circuit; earth, battery, winding of relay 240, contacts 251 and 263, wiper 273 of the test distributor, and wiper 293 of the test connector. It is self-evident that relay 240 will operate over the above circuit only if contact 296 is at earth potential.

Assuming that the subscriber's line 101 is idle, contact 296 normally will not be at earth potential, and hence relay 240 will not operate. Relay 260, upon restoring, opens the above-described circuit for the test relay 240 at contact 263, and at the same time completes the following circuit over contact 264: earth, contacts 241 and 264, wiper 273 of the test distributor, wiper 293 of the test connector, contact 296, conductor 119, middle winding of two-step relay 120, battery and earth. Responsive to its energization over this circuit, relay 120 operates all of its contacts; at contacts 121 and 122 it disconnects itself from the conductors 115 and 116 of the line 101 in order to clear the line of attachments. The opening of contact 124 insures that no finder switch will be set in motion with line 101.

At contacts 261 and 262 the test circuit 210 is switched through so that conductors 211 and 212 are in direct connection with conductors 115 and 116, respectively. Accordingly, by means of appropriate testing equipment which may be connected to the conductors 211 and 212 at the test desk, the test operator now is able to make such tests as he desires upon the line 101. Suitable test desk equipment is shown in the Crocker patent.

Assuming now that the subscriber's line 101 is not idle at the time the test operator extends the connection to it over his test switch trains but instead is engaged in a call, contact 296 in the bank of the test connector will be at earth potential as is well known. The operations in this case will be the same as those previously described up to the point where relay 250 restores. When this occurs, test relay 240 will operate due

to the presence of earth potential on bank contact 296, and will prepare an alternate circuit for itself by closing contact 242. Accordingly, upon the release of relay 260 a moment later, relay 240 will remain operated due to its energization over the following circuit: earth, battery, winding of relay 240, contacts 242 and 264, wiper 273 of the test distributor, wiper 293 of the test connector, and earth on the bank contact 296.

The operation of relay 240 brings in a signal at the test desk to notify the operator that the line with which connection has been made tests busy. He will then associate his telephone set with the conductors 211 and 212, and, by listening for speech, verify the fact that the line is in use. Finding a call to be in progress, he may for the moment abandon his attempt to test the line and release the connection which he has established thereto, or, alternatively, he may wait for the line to become idle. It will be assumed that he elects to follow the latter course.

When the apparatus involved in the inter-subscriber connection is released upon termination of the call, it removes earth from contact 296 in the bank of the test connector. Thereupon, relay 240 will restore, and at contact 241 will complete the following circuit for operating the two-step relay 120: earth, contacts 241 and 264, wiper 273 of the test distributor, wiper 293 of the test connector, bank contact 296, conductor 119, middle winding of relay 120, battery and earth. As previously explained, relay 120 operates all of its contacts when it is energized over this circuit. Accordingly, it disconnects itself from the line 101 at contacts 121 and 122 and opens contact 124 to insure that no finder switch will be started searching for the line 101. The disconnection of relay 120 from the line conductors clears the line of attachments, and therefore the test operator may now proceed with his test over the conductors 211 and 212, as in the case already described.

The procedure involved in making a test upon the subscriber's line 301 is substantially the same as that for testing the line 101. Obviously, in this case the test connector will be operated to set its wipers 291, 292 and 293 upon bank contacts 297, 298 and 299, respectively. If the line 301 is busy, bank contact 299 will be at earth potential, and test relay 240 will be operated upon the restoration of relay 250, as should be clear from the previous description; if, on the other hand, the line is idle, there normally will be no earth potential upon contact 299 and relay 240 will not be operated.

Assuming first that line 301 is idle, the following circuit will be established upon the release of relay 260 in the test distributor: earth, contacts 241 and 264, wiper 273 of the test distributor, wiper 293 of the test connector, bank contact 299, conductor 319, contact 321, winding of relay 325, battery and earth. Relay 325 operates responsive to energization over this circuit, and at contacts 324 and 326 disconnects relay 320 from conductors 315 and 316 thereby to clear the line 301 of attachments. Relay 325 also closes contact 306, causing relay 305 to operate, but the latter relay performs no useful function at this time. The closing of contacts 261 and 262 in the test distributor completes a direct connection from conductors 211 and 212 of the test circuit to conductors 315 and 316, respectively, of line 301, so that the test operator may proceed with his test in the usual way. Had the line 301 been busy instead of idle, test relay 240 in the

test distributor would have locked up to earth on bank contact 299 until the line became idle, as explained in connection with the test made upon line 101; responsive to the removal of earth from contact 299 when line 301 became idle, test relay 240 would restore, and, by closing contact 241 would operate relay 325 over the circuit set forth above. This places the line in proper condition for testing by disconnecting relay 320 from it.

After the operator has extended a connection over the test switch train to a subscriber's line in the way described and has received an indication that the line tests busy, it sometimes happens that, by means of his listening test, he determines that no conversation is in progress. Under such circumstances he will, of course, wish to proceed with the usual tests upon the line. Ordinarily, however certain attachments are bridged across the subscriber's line in the exchange; in the past the operator has been unable to remove such attachments from the line, and hence he frequently has been compelled to abandon his attempt to test the line over the connection extended thereto from the test desk, and has had, instead, to resort to the inconvenient practice of testing the line directly at the main distributing frame, where the attachments can be removed by opening the jumpers (such as 113, 114 or 313, 314).

The reasons for this difficulty will be made clearer by an explanation of what takes place when a permanent exists on a subscriber's line. As is well known, a permanent may result from the line conductors being accidentally bridged as shown at X, from one of the conductors being accidentally grounded as shown at Y, or from a combination of these two causes. In all such cases, the same result is produced. It will be assumed, therefore, in order to illustrate the problem, that the conductors 111 and 112 of line 101 have become bridged as shown at X. This bridge simulates a calling condition by completing the following circuit: earth, lower winding of the two-step relay 120, contact 122, conductor 116, jumper 114 at the main distributing frame, conductor 112, the bridge X, conductor 111, jumper 113 at the main distributing frame, conductor 115, contact 121, upper winding of relay 120, middle winding of relay 120, battery and earth. Responsive to its energization over this circuit, relay 120 takes its first step, operating contacts 123 and 125, but no others. Contact 123 characterizes the subscriber's line 101 in the banks of finder switches having access to that line, by completing a circuit from earth via battery, the middle winding of relay 120, conductor 119, and contact 123 to finder switch bank contacts such as 133. At the same time contact 125 completes an obvious circuit over conductor 137 for causing the distributor 150 to start a finder switch of one of the links searching for the characterized line.

Assuming that the distributor has connected with the finder switch of link 140 over a hunter switch 155, that finder switch will move its wipers 134, 135 and 136 until they engaged the bank contacts 131, 132 and 133, respectively, of the line 101. Thereupon, as is well known, the movement of the wipers is halted, and switching relay 160 is operated by earth connected for a brief interval to conductor 165. Relay 160 upon operating completes the following circuit: earth on conductor 165, contacts 164 and 163, finder switch wiper 136, bank contact 133, contact 123, conductor 119, middle winding of the two-step relay

120, battery and earth. Responsive to energization over this circuit, relay 120 now takes its second step, thereby operating the remainder of its contacts; at contact 124 it opens the start circuit extending to the distributor over conductor 137, while at contacts 121 and 122 it disconnects itself from conductors 111 and 112 of the subscriber's line.

Returning to the operation of switching relay 160 in the finder, it will be seen that this, at contacts 161 and 162, extends the line loop to the line relay 170 of the selector switch. Thereupon relay 170 operates over the following circuit: earth, lower winding of relay 170, contact 162, finder switch wiper 135, bank contact 132, conductor 116, jumper 114, conductor 112, the bridge X, conductor 111, jumper 113, conductor 115, bank contact 131, finder switch wiper 134, contact 161, upper winding of relay 170, battery and earth. Relay 170 closes contact 171 thereby operating the slow release relay 180, and the latter in turn closes contact 181.

It should be mentioned that certain known arrangements, for example the one shown in the above-mentioned patent to Lomax et al., depart from the mode of operation just described to the extent that the relay 170 is operated over a pre-energizing circuit (not shown) before contacts 161 and 162 are closed; when this practice is followed, however, the said pre-energizing circuit is opened after the line 101 has been switched through to relay 170 by the closure of contacts 161 and 162, so that relay 170 is maintained energized over the line loop, as described. In either event, the operation of relay 180 due to the closing of contact 171 occurs before earth is removed from conductor 165, so that, upon such removal, relays 160 and 120 are maintained operated from earth at contact 181. The holding circuit for relay 160 may be traced from earth over contact 181, contact 164, winding of relay 160, and battery to earth. The holding circuit for the relay 120 may be traced from earth over contact 181, contact 163, finder switch wiper 136, bank contact 133, contact 123, conductor 119, middle winding of relay 120, and battery to earth.

It will be appreciated that the operations described above, which have taken place as a result of the conductors 111 and 112 becoming bridged at X, are exactly the same as would have taken place if a bona fide call had been originated by the subscriber removing the telephone receiver at substation 100 from its switchhook. They bring about the conditioning of the selector switch to receive the call-directing impulses which, in the case of a bona fide call, would now be transmitted from substation 100 by the subscriber's operation of the dial. Quite obviously no such impulses will be transmitted in the case under consideration, and accordingly, unless some special steps are taken, the apparatus will remain in the condition described so long as the bridge at X persists.

Let it now be assumed that this case is the status of the equipment at the time the test operator extends a connection to line 101 over the test distributor and test connector. Upon the release of relay 250 in the test distributor after the final setting of the test connector wipers, the usual test is made to determine whether line is busy or idle; this test results in the operation of test relay 240 over the following circuit: earth, battery, winding of relay 240, contacts 251 and 263, wiper 273 of the test distributor, wiper 293

of the test connector, bank contact 296, conductor 119, contact 123, bank contact 133, wiper 136 of the finder switch, contact 163, contact 181, and earth. Test relay 240 upon operating prepares an alternate circuit for itself, so that when relay 260 releases a moment later, relay 240 is maintained energized over the following path: earth, battery, winding of relay 240, contacts 242 and 264, wiper 273 of the test distributor, wiper 293 of the test connector, bank contact 296, conductor 119, contact 123, bank contact 133, wiper 136 of the finder switch, contact 163, contact 181, and earth. It will be seen that now relays 120, 160 and 240 all are maintained operated by the earth at contact 181 of the selector switch.

The operator of test relay 240 brings in the busy signal at the test desk as previously explained, whereupon, by associating his telephone set with the test circuit 210, the operator can determine that no conversation is in progress. Although the test circuit is in direct connection with conductors 115 and 116 of the subscriber's line, the fact that relay 170 is also connected to conductors 115 and 116 militates against the operator making a satisfactory test upon the line. It is this fact which has, in the past, made it necessary for permanent lines to be tested at the main distributing frame with the exchange equipment disconnected, rather than over the test switch train.

According to the present invention it is possible for the test operator to free the line 101 of attachments despite the existence of the permanent condition thereon, and to proceed with his test over the test switch train. To do this, he momentarily operates the manual switch key 215 at the test desk. This completes a circuit extending from earth, over resistance 218, switch contact 216, conductor 211, contact 221, contact 261, test distributor wiper 271, test connector wiper 291, bank contact 294, conductors 117 and 115, finder switch bank contact 131, finder switch wiper 134, contact 161, upper winding of relay 170, and battery to earth; it also completes the following circuit: earth, booster battery, resistance 219, switch contact 217, conductor 212, contact 222, contact 262, wiper 272 of the test distributor, wiper 292 of the test connector, bank contact 295, conductors 118 and 116, bank contact 132, finder switch wiper 135, contact 162, lower winding of relay 170, and earth. The first of these two circuits insures that current will continue to flow over the upper winding of relay 170 in the same direction that it did before switch key 215 was operated, while the latter circuit causes a reversal of the current flow through the lower winding of relay 170. Whereas the two windings of relay 170 previously aided one another, they now are in opposition, resulting in a differential action which causes the relay to restore. In consequence thereof, contact 171 is opened, permitting relay 180 to restore, which thereupon opens contact 181. The opening of contact 181 initiates the release of relays 160, 120 and 240.

Relay 160 restores first, thereby opening its contacts and also, in the well known way, initiating the release of the finder switch. Next, relays 120 and 240 restore substantially simultaneously. Relay 240 upon restoring closes contact 241, which completes a previously traced path for re-energizing the middle winding of relay 120. Therefore, relay 120 immediately reoperates all of its contacts. It will be seen that the release

of relay 160 has disconnected relay 170 from the conductors of the subscriber's line, first by opening contacts 161 and 162 and then, shortly afterward, by the restoration of the finder switch wipers 134, 135 and 136 to normal. In view of this fact, and the additional fact that relay 120 now has also been disconnected from the line conductors due to the opening of contacts 121 and 122, the subscriber's line is free of attachments in the exchange. Accordingly, the operator, having restored the key 215 to normal, may proceed with his test upon the line in the usual way by means of equipment at the test desk which he associates with the test circuit 210.

Turning now to an examination of what takes place when a permanent exists upon subscriber's line 301 which is provided with an arrangement for locking out that line, it will be assumed for illustrative purposes that the line has accidentally become grounded as shown at Y. This completes the following circuit: earth, at Y, conductor 311, jumper 313 at the main distributing frame, conductor 315, contact 324, upper winding of relay 320, battery and earth. Relay 320 operates responsive to its energization over this circuit, and at contact 329 connects earth to conductor 319 to characterize the line as busy in the banks of connector switches. At contact 322 it characterizes the subscriber's line 301 in the banks of 30 finder switches having access to that line, by completing a circuit from earth via battery, winding of relay 325, contacts 302 and 322 to finder switch bank contacts such as 333; at the same time, by closing contact 323, it completes a start circuit 35 over contact 304 and conductor 337 to the distributor 350. Thereupon the distributor causes the finder switch of one of the links, say 340, to search for the characterized line.

When the finder switch wipers 334, 335 and 336 40 come into engagement with contacts 331, 332 and 334, respectively, their movement is halted in the known manner, and relay 360 is operated by earth connected for a brief interval to conductor 365. Relay 360 upon operating completes the following 45 circuit for relay 325: earth on conductor 365, contacts 364 and 363, finder switch wiper 336, bank contact 333, contacts 322 and 302, winding of relay 325, battery and earth. Relay 325 operates, and at contact 327 closes an alternate circuit for 50 its own winding so that it will remain operated independently of contacts 302 and 322, which are soon to open. At contact 306 relay 325 completes an obvious circuit for relay 305, while at contacts 324 and 325 it disconnects relay 320 from the line 55 conductors of the subscriber's line. Relay 320 releases, thereby interrupting the start circuit to the distributor by opening contact 323. It also interrupts the original operating circuit for relay 325 by opening contact 322, but this is without 60 effect since, as already pointed out, relay 325 will remain energized over its own contact 327. Earth now is maintained on conductor 319 over contacts 321 and 327. Relay 305 operates due to the closing of contact 306. At contact 303 it prepares 65 an alternative circuit for its own winding, while at contact 308 it prepares a circuit to the permanent lock out alarm; its other contacts perform no useful function at this time.

Returning to the operation of switching relay 70. 360 in the finder switch, it will be seen that this, at contacts 361 and 362 extends the line conductors to the line relay 370 of the selector switch. Thereupon, relay 370 operates (or, if it was pre-energized as shown in the patent to Lomax et al., 75 the preenergizing circuit now is interrupted, and

the relay is held operated) over the following circuit: earth, battery, upper winding of relay 370, contact 361, finder switch wiper 334, bank contact 331, conductor 315, jumper 313 at the main distributing frame, conductor 311, and earth at Y. The closing of contact 371 completes an obvious circuit for relay 380, and the latter relay closes contact 381 before earth is removed from conductor 365, thereby to maintain relays 360 and 325 operated. The holding circuit for relay 360 extends from earth over contacts 181 and 364, winding of relay 365 and battery to earth. The holding circuit for relay 325 extends from earth over contacts 381 and 363, finder switch wiper 336, bank contact 333, contact 327, winding of relay 325, and battery to earth.

It will be recognized that the link 340 has been conditioned to receive the call-directing impulses which, in the case of a bona fide call, would now be transmitted from the substation 300 by the subscriber's operation of the dial. Since no impulses are received within a certain time, relay 400 is operated in the well known way, which, by opening contact 401, causes relay 380 to release. In consequence thereof, contact 381 is opened, and causes relays 360 and 325 to release.

Relay 360 upon restoring opens its contacts and initiates the release of the link 340, whereby the finder switch wipers 334, 335 and 336 are restored to normal and the link 340 is made free to handle calls over other lines. Relay 325 upon restoring reconnects relay 320 to the line conductors by closing contacts 324 and 326; opens its own circuit at contact 327; opens the circuit for relay 305 at contact 306; and, at contact 307, completes a circuit over contact 308 and conductor 309 to the permanent lockout alarm. Due to its slow-to-release characteristic, relay 305 will not at once restore; meanwhile relay 320 reoperates over the following path: battery, earth, upper winding of relay 320, contact 324, conductor 315, jumper 313, conductor 311, and earth at Y. The operation of relay 320 prevents relay 305 from restoring by completing the following circuit: earth, contact 323, contact 303, winding of relay 305, battery and earth. Contact 322 is closed but has no effect since contact 302 is open, and it will be seen that earth again is applied to conductor 319 over contact 329. Line 301 now is locked out.

Let it be assumed that the line 301 is thus locked out at the time the test operator extends his connection thereto over the test switch train. After the final setting of the test connector wipers upon bank contacts 297, 298 and 299, relay 250 releases and the usual test is thereupon made to determine whether the line is busy or idle; this test results in the operation of test relay 240 over the following circuit: earth, battery, winding of relay 240, contacts 251 and 263, wiper 273 of the test distributor, wiper 293 of the test connector, bank contact 299, conductor 319, contact 329 and earth.

The operation of test relay 240 will bring in the busy signal at the test desk, as already noted, whereupon the operator, by connecting his telephone set to the test circuit 210, will ascertain that no conversation is in progress. Accordingly, he

will operate the manual key 215 momentarily in order to clear the line of the attachment represented by relay 320 being connected to the line conductors over contacts 324 and 326. The operation of the key completes a circuit extending from earth, over resistance 218, contact 216, conductor 214, contact 221, contact 261, wiper 271 of the test distributor, wiper 291 of the test connector, bank contact 297, conductor 317, conductor 315, contact 324, upper winding of relay 320, and battery to earth; it also completes the following circuit: earth, booster battery, resistor 219, contact 217, conductor 212, contact 222, contact 262, wiper 272 of the test distributor, wiper 292 of the test connector, bank contact 298, conductor 319, contact 326, lower winding of relay 320, and earth. The first of these two circuits insures that current will continue to flow over the upper winding of relay 170 in the same direction as it did before switch key 215 was operated, while the latter circuit causes current to flow through the lower winding of relay 320 in such a direction as to neutralize the effect of the upper winding. Accordingly, relay 320 will restore. At contact 329 the circuit for relay 240 is opened, and at contact 323 the circuit for the slow relay 305 is opened. Relay 240 releases before relay 305, and at contact 241 completes the following circuit: earth, contacts 241 and 264, wiper 273 of the test distributor, wiper 293 of the test connector, bank contact 299, conductor 319, contact 321, winding of relay 325, battery and earth. Relay 325 operates responsive to its energization over this circuit, and at contact 306 it completes a circuit for relay 305, thereby preventing the latter relay from restoring. The opening of contact 307 upon operation of relay 325 interrupts the circuit to the permanent lockout alarm, while the opening of contacts 324 and 326 disconnect relay 320 from the conductors of line 301. The disconnection of relay 320 from the line conductors has cleared line 301 of attachments, and it now may be tested over the test switch train from the test desk in the usual way.

Having described the invention, what is considered new and is desired to be protected by Letters Patent is set forth in the following claims.

What is claimed is:

1. In a telephone system, subscribers' lines upon which faults occur at times, a test operator's position, operator-controlled switching equipment for extending a connection from said position to a line upon which a fault exists, means controlled from said position over said connection and one of the line conductors of said faulty line for clearing said line conductors of attachments preparatory to making a test upon them, and means then effective to maintain said line conductors cleared of attachments independently of any control over said one line conductor.

2. In a telephone system wherein a relay is connected to at least one of the conductors of a telephone line when a certain fault occurs on that line, a test operator's position, operator-controlled means for completing a connection from said position to the line conductors of said faulty line, means at said position operated to apply a potential to said connection, thereby to operate said relay over said connection and said one line conductor, and means controlled by said relay, upon such operation, for disconnecting said relay from the line to permit said line to be tested without said relay connected thereto.

3. In a telephone system wherein a certain fault on any one of a group of subscribers' lines

causes that line to seize switching equipment common to the lines of said groups, a test operator's position, operator controlled means for extending a connection from said position to said faulty line, and means in said common equipment controlled from said position over said connection and a line conductor of said faulty line for forcibly releasing said common equipment and for clearing said line of attachments preparatory to making a test upon said line.

4. In a telephone system, subscribers' lines, switching equipment common to said lines, means for causing said equipment to connect with any one of said lines, an operator's position, operator controlled means for extending a connection from said position to the line conductors of said one line while said switching equipment is connected to that line, a booster battery, operator controlled means for connecting said booster battery to said connection, and means in said switching equipment controlled by said booster battery over the line conductors of said one line and said connection extended thereto from said position for forcibly disconnecting said switching equipment from said one line responsive to said booster battery being connected to said connection.

5. In a telephone system, subscribers' lines, switching equipment common to said lines, means for causing said equipment to connect with any one of said lines, a booster battery, means for connecting said booster battery to the line conductors of said one line while said common switching equipment is connected thereto, and means in said switching equipment controlled over the line conductors of said one line by said booster battery for forcibly disconnecting said switching equipment from said one line responsive to said connection of said booster battery to said line conductors.

6. In a telephone system, subscribers' lines, means for making any of said lines busy, an operator's position, operator controlled means for extending a connection from said position to the line conductors of one of said busy lines, a booster battery, operator controlled means for connecting said booster battery to said connection, a device connected to the line conductors of said one line and operated, over said conductors and said connection extended thereto, by said booster battery, said first means thereupon controlled by said operation of said device to make said one line idle.

7. In a telephone system, a subscriber's line having two line conductors, a line relay having two windings connected respectively to the two conductors of said line, means for energizing said two windings over said line in such a way that they assist one another in maintaining said relay operated, means for at times reversing the direction in which one of said windings is energized and, at the same time, maintaining the other winding energized in its original direction, thereby to cause said relay to restore due to the differential action of its two windings, and means operated responsive to the restoration of said relay at such times for disconnecting the two windings of said relay from said line conductors.

8. In a telephone system, a subscriber's line having two line conductors, a line relay having two windings connected respectively to the two conductors of said line, means for energizing said two windings over said line in such a way that they assist one another in maintaining said relay operated, means controlled by said relay when thus operated for making said line busy,

means for at times reversing the direction in which one of said windings is energized and, at the same time, maintaining the other winding energized in its original direction, thereby to cause said relay to restore due to the differential action of its two windings, said second means controlled by said relay responsive to its restoration to make said line idle.

9. In a telephone system, a subscriber's line having two line conductors, a relay having two windings connected respectively to the two conductors of said line, means for energizing at least one of said windings over said line thereby to maintain said relay operated, a booster battery, means operated at times to connect said booster battery to one of said line conductors, said battery thereupon effective to cause current to flow in the other winding of said relay in such a direction as to oppose the effect of said one winding, thereby to restore said relay to normal, and means operated responsive to said restoration of said relay to normal for disconnecting the two windings of said relay from said line conductors.

10. In a telephone system, a subscriber's line having two conductors, a relay having two windings connected respectively to the two conductors of said line, means for energizing at least one of said windings over said line thereby to maintain said relay operated, and means operated at times to cause current to flow in the other of said windings in such a direction as to oppose the effect of said one winding, thereby to cause said relay to release.

11. In a telephone system, a subscriber's line having two conductors, a relay having two windings connected respectively to the two conductors of said line, means for energizing at least one of said windings over said line thereby to maintain said relay operated, means operated at times to cause current to flow in the other of said windings in such a direction as to oppose the effect of said one winding, thereby to cause said relay to release, and means responsive to the release of said relay for maintaining it released independently of said second means.

12. In a telephone system, a subscriber's line, a relay connected to at least one of the line conductors of said subscriber's line, a booster battery, means for connecting said booster battery to said conductor, and means controlled by said relay responsive to the connection of said booster battery to said conductor for disconnecting said relay from said line.

13. In a telephone system, a subscriber's line, a relay connected to at least one of the line conductors of said subscriber's line, a booster battery, means for connecting said booster battery to said conductor, and means controlled by said relay responsive to the connection of said booster battery to said conductor for disconnecting said relay from said line and maintaining it disconnected independently of said booster battery.

14. In a telephone system, subscribers' lines, equipment common to said lines, means at times controlled over one of said lines for seizing said equipment, a relay in said equipment thereupon connected to the speech path of said one subscriber's line, a booster battery, means for connecting said booster battery to said speech path, and means controlled by said relay responsive to said connection of said booster battery to said path for releasing said equipment.

15. In a telephone system, subscribers' lines, equipment common to said lines, means at times controlled over one of said lines for seizing said

equipment, a relay in said equipment thereupon connected to the speech path of said one subscriber's line, a booster battery, means for connecting said booster battery transitorily to said speech path, means controlled by said relay responsive to said transitory connection of said booster battery to said path for releasing said equipment, and other means controlled by said relay responsive to said transitory connection of said booster battery to said path for preventing said first means from again seizing said common equipment after said booster battery has been disconnected from said path.

16. In a telephone system, a subscriber's line, means for making said line busy, switching equipment operated to extend a connection to said line while same is busy, a source of booster battery potential, means for impressing said potential upon one of the line conductors of said line over said connection, a relay individual to said subscriber's line connected to said one conductor and operated responsive to the connection of said potential to that conductor, thereby to cause said line to become idle, a device in said switching equipment operated responsive to said line becoming idle, and means controlled by the opera-

tion of said device for disconnecting said relay from said line conductor.

17. In a telephone system, subscribers' lines, switching equipment common to said lines, means controlled over any one of said lines for seizing said equipment and associating it individually with said one line, a relay in said equipment thereupon connected to one of the line conductors of said one subscriber's line, means in said equipment for making said one line busy, other switching equipment operated to extend a connection to said one line while same is busy, a source of booster battery potential, means for impressing said potential upon said one line conductor over said connection, said relay operated responsive to said potential being impressed upon said one line conductor to cause said second means to make said line idle, means in said first switching equipment operated responsive to said line becoming idle for disconnecting said relay from said one line conductor, and means in said other switching equipment operated responsive to said line becoming idle for at once making it busy again.
